CATALYTIC CONVERSION OF HYDROCARBON OILS

Alex G. Oblad, Springfield, and Heinz Heinemann, Drexel Hill, Pa., assignors to Houdry Process Corporation, Wilmington, Del., a corporation of Delaware

Application November 30, 1950, Serial No. 198,467

11 Claims. (Cl. 196—49)

The present invention relates to catalytic conversion of hydrocarbons above the gasoline boiling range, such as topped crude oils, to high yields of gasoline of good anti-knock quality. The invention is particularly concerned with catalytic cracking of such hydrocarbons at high pressure in the presence of excess hydrogen and the processing of selected portions of the cracked effluent to effect conversion of substantially the entire initial charge to high yields of gasoline of good octane rating.

Among the objects of the invention is to provide an efficient process for the conversion of higher boiling oils to quantities of high quality gasoline almost equal to or exceeding 100% by volume of the charge.

In accordance with the invention a hydrocarbon charge stock of above gasoline boiling range, such as a reduced crude petroleum oil obtained by topping the oil to remove low boiling ends including gasoline and/or light naphthas, is hydrogenatively cracked in the presence of added hydrogen and under a pressure in excess of about 750 pounds per square inch while in contact with a catalyst composed of a cracking component intimately associated with a relatively minor amount of a component having selective hydrogenating activity. The cracked vapor effluent is condensed and fractionated to provide a high octane light gasoline fraction and a naphtha fraction of relatively poor octane quality including largely components boiling in the gasoline range, while the residual bottoms are recycled to the hydrogenative cracking zone; all of the charge being thus ultimately cracked to gasoline and lighter hydrocarbons. The poor octane naphtha fraction which will be rich in naphthenes convertible to aromatics, is upgraded under catalytic dehydrogenation conditions and the reformed naphtha thus produced is added to the high octane light gasoline fraction from the catalytic cracking step. Advantageously, hydrogen produced in the dehydrogenation of the naphtha is recycled to the hydrogenative cracking step; if desired, light gaseous hydrocarbons formed in hydrogenative cracking can be decomposed by coking in the presence of catalyst or otherwise, to provide additional hydrogen which can be recycled for use in the hydrogenative cracking step. The flow chart in the accompanying drawing illustrates a practical adaptation of the invention. The operation of the invention will be understood from the description which follows read in connection with the accompanying flow chart illustrating a preferred processing operation.

The topped crude charge (1) which may contain the entire bottoms, preferably after removal of at least part of the mineral salt content, is heated to reaction temperature and together with added hydrogen or hydrogen rich gas (2) in required proportions is continuously charged at controlled rates to the hydrogenative cracking zone (3), which is maintained under required conditions of temperature and pressure. The cracked product is fractionated (4) to separate the same (in order of increasing boiling range) into hydrogen (5), light normally gaseous hydrocarbons in the C₁—C₃ range (6), a C₄ fraction (7), a high octane C₅—C₆ cut (8), a naphtha cut including higher boiling components of the gasoline range (9) and residual bottoms (10).

The residual bottoms fraction from the hydrogenative cracking is recycled to the hydrogenative cracking zone (3) as well as the excess hydrogen (5). The naphtha cut (9) is passed to a dehydrogenation zone (11) where it is upgraded principally by conversion of naphthenes to aromatics in the presence of a dehydrogenation catalyst, the effluent therefrom being distilled (12) to produce a re-

2

formed naphtha fraction (13); and the residue from this distillation, above desired gasoline boiling range, is recycled (14) to the hydrogenative cracking step. Hydrogen produced in the dehydrogenation is recovered (15) and the hydrogen rich gas returned for use in the hydrogenative cracking step. The reformed naphtha (13) is blended with the previous high octane C₅—C₆ cut from (8), and the blend adjusted and stabilized by addition of a suitable quantity of the C₄ product from (7) as indicated at (16), to furnish gasoline of desired vapor pressure.

As indicated, the hydrogen produced in the dehydrogenation step (11) is advantageously recycled to the cracking step which uses up hydrogen. Additional hydrogen is available from coking of the fixed gas from (6) so that by employing the latter step the process can be made almost or entirely self-sufficient in hydrogen requirements. Coking may be effected, as indicated at (17) by thermal or catalytic decomposition of the fixed gas. The present invention is not limited to any particular method of coking of the fixed gas and various means will be apparent to those skilled in the art. For instance, the gas may be converted by reaction with steam to CO or CO₂ plus hydrogen as in the known water-gas processes, in the presence of nickel oxide or other suitable catalyst, and the hydrogen-rich gas evolved recovered (18) and recycled to the hydrogenative cracking zone.

It will be understood that in practical operation of the described process, suitable provision will be made in known manner for heat exchange of products and charge as may be convenient, as well as for adjustment of pressure and temperature for desired stripping of gases, condensation of liquid products and repressuring of the recycled fraction.

Although other feed stocks, such as heavy gas oils or residuum from thermal or catalytic cracking may be used as charge for hydrogenative cracking in zone 3, one of the important advantages of the present process lies in the fact that high boiling portions of the crude oils including the tars and bottoms can be efficiently handled therein. Removal of at least a portion of the salts generally contained in the crude oil is recommended particularly with stocks other than those of naturally low salt content.

While such removal is not indispensable for operation of the present process, the accumulation of such salts or residues therefrom in the cracking zone in addition to increasing corrosion problems, may shorten the on-stream periods of operation and deactivate the catalyst to the extent of curtailing the useful life thereof. Desalting may be effected in known manner, for instance by chemical or electrical methods or by heating and settling, capable of reducing the salt content to preferably less than 5-10 pounds per 1000 barrels of oil; centrifuging may be found advantageous. If the reduced crude charged to the hydrogenative cracking zone is one which has had as much as 5-10% of the bottoms removed by deasphalting or tar separation procedures, the removed portion will contain the preponderant part of the salts and separate desalting of the reduced crude in such cases ordinarily will not be practiced.

In the hydrogenative cracking zone, the conditions are preferably maintained to favor hydrogenative cracking of the charge without excessive formation of low molecular weight gases and with little or practically no incremental coke production, such that the process can be operated for comparatively long periods without necessitating periodic catalyst regeneration. These conditions include pressures above 750 pounds per square inch, temperatures of about 800 to 1000° F., and space rates of up to about 6 volumes of oil (as liquid) per hour per volume of catalyst, hydrogen being added with the charge at the rate of 3 or more mols per mol to total hydrocarbon charged. In the preferred operation pressures of 1500 to 3500 pounds are employed at temperatures below 900° F. and space rates of about 0.5 up to about 4, hydrogen being added at rates of at least 5 mols and up to 10-15 mols per mol of total hydrocarbon charged. As catalyst there may be employed composited contact masses composed of a component having cracking activity intimately associated with a small portion of a component having hydrogenative activity. The pre-

ferred composited catalysts are those in which the cracking component is one of comparatively high cracking activity, such as acid activated montmorillonite clays, dried siliceous gels of the silica-alumina and silica-magnesia type, and HF-activated alumina. The hydrogenating component is likewise one of selective high activity for this function and is preferably an oxide of nickel or molybdenum, the former in amounts of up to 5% by weight of the catalyst and the latter generally in smaller amount as up to about 2% by weight of the catalyst.

The operating conditions in the hydrogenative cracking step are selected and correlated to obtain only moderate conversion severity particularly if regeneration of the catalyst is not desired to be practiced, and to avoid loss of large amounts of the hydrocarbon charge to the formation of low molecular weight hydrocarbon gases. In general, it is preferred to operate under conditions obtaining about 20-60% conversion per pass, or stated otherwise at recycle ratios of about 1/1 to 4/1.

In the above described type of operation the catalytic gas oil is recycled to extinction, that is until it is converted entirely to gasoline of desired end point with the concomitant formation of C₄ hydrocarbons and lower molecular weight hydrocarbon gases. The choice of conversion severity will be governed largely by the butane requirements for the gasoline produced in the process or needed elsewhere in the refinery. With increasing severity there is a corresponding increase in formation of C₄ hydrocarbons accompanied by an increase in the amount of lower molecular weight hydrocarbon gases produced. At lower conversion levels, of course, there is a smaller amount of C₄ hydrocarbons and lower molecular weight gases formed, but likewise the amount of gasoline produced per pass is also lowered, so that increased recycle ratios are required and as a result thereof the amount of fresh feed that can be converted in a given time in the reactor of fixed capacity is correspondingly reduced.

In hydrogenative cracking operations carried out under the conditions above described, for most of the usual charge stocks, continuous on-stream periods as long as six months or more are possible. The length of the continuous on-stream period will depend almost entirely on the salt content of the charge and ability of the reactor and the catalyst to accumulate this salt without affecting the desired hydrocarbon conversion reactions, since outside of a possible initial deposition of a negligible quantity of coke at the beginning of the on-stream period there is no incremental coke deposition during continuous operation of the hydrogenative cracking process. Heavy metals that may be deposited in the catalyst from the charge are not necessarily detrimental and may even serve to enhance the hydrogenative function of the catalyst.

The following illustrates typical results obtained in a hydrogenative cracking operation carried out for several days on an entire bottoms fraction of East Texas crude oil (40% residuum) of 23.7 API gravity and boiling in the range of 430° F. initial, 50% at 855° F., 80% at 985° F. The operating conditions employed were 825° F. at a total pressure of 3500 p. s. i., at a space rate of one volume of oil per hour per volume of catalyst. 6 mols of hydrogen being added per mol of total hydrocarbon charged; the catalyst being 2.0% NiO on synthetic silica-alumina gel (87.5 SiO₂-12.5 Al₂O₃). For total conversion of the charge to gasoline and lighter hydrocarbons a recycle ratio of 3.8 was employed, with the following ultimate yields:

Gasoline, 385° F. at 90%; vol. percent fresh feed	102.8
C ₄ cut, vol. percent fresh feed	16.6
Dry gas, wt. percent fresh feed	10.1
Coke	Nil

The particular cut point to be employed for the recycled catalytic gas oil (or the end point of the gasoline to be sent to reforming) will depend largely on the nature of the initial fresh charge and the chemical composition or octane rating of various successive narrow cuts taken in the 350-450° F. boiling range of the hydrogenatively cracking effluent (synthetic crude). In the particular embodiment illustrated in the accompanying flow chart materials boiling above 370° F. are recycled to the hydrogenative cracking zone 3. In other operations, depending upon the charge stock and on the desired final products, it may be preferred to cut the gas oil for re-

cycling at a higher or lower point as for instance at 350° F. or at a point as high as 450° F.

Like considerations apply in the selection of the initial cut point for the low octane naphtha fraction sent to reforming (9). This cut, of course, will include all of the hydrocarbons boiling below the recycled gas oil exclusive of the light ends (8). As a general rule reforming of products boiling below about 180° F. need not be practiced, and in some instances it may be preferred to reform only the products above a higher cut point as those boiling above about 220-240° F.

The reforming of the naphtha is carried out under conditions favoring dehydrogenation of naphthenes and is preferably unaccompanied by material cracking of the charge. For use in this step known dehydrogenation catalysts of the indicated selectivity can be employed such as those containing up to 8-15% molybdena on activated alumina, or nickel or nickel oxide on various inert carriers. Catalysts which have significant cracking activity, even if in addition to dehydrogenating activity, are best avoided in the reforming operation. A preferred catalyst for use in this step is that disclosed in our copending application Serial No. 198,469, filed November 30, 1950, comprising Pt on an inert support, which support has no significant cracking activity, such as 0.1 to 2% Pt on MgO. Operating conditions for reforming by dehydrogenation include temperatures of about 700-1050° F., the preferred operating temperature lying in the neighborhood of 950° F. From overall considerations pressures in the range of 500 to 1500 p. s. i. are favored since at increased pressures of about 2000 p. s. i. the cracking reaction is promoted with consequent increased gas production, while at low pressures in the order of about 300 p. s. i. considerable coke formation takes place. Hydrogen to oil ratios similar to those heretofore disclosed for the cracking operation can be used; ratios as low as 3.0 mols H₂ per mol of naphtha have been found satisfactory. The space velocity should be adjusted to favor dehydrogenation and to avoid side reactions such as cracking, so that higher space rates are generally preferred above about one volume of oil per hour per volume of catalyst and up to about 10.0. The process variables can be so selected to avoid significant coke formation, enabling practice of a non-regenerative process. Even if it is desired to operate at higher severity to obtain optimum octane upgrading, long on-stream periods of several days or more are possible between regenerations.

The following results obtained in the dehydrogenation of an East Texas straight-run naphtha are typical:

Table

Naphtha charged cut.....		East Texas, 180-375° F.		East Texas 230-375° F.

Since the reforming operation carried out at 11 involves essentially dehydrogenation of naphthenes there will be an overall net production of hydrogen, which as indicated in the accompanying flow chart may be recycled to the hydrogen deficient hydrogenative cracking step.

The described process involving hydrogenative cracking with dehydrogenative reforming of a selected naphtha cut therefrom and recycling of the higher boiling catalytic gas oil, permits conversion of topped crude oils or of other 80 recycle stocks including catalytically or thermally cracked recycle stocks to 90-110 vol. per cent gasoline of desired high octane quality and good lead susceptibility, producing comparatively small amounts of excess C₄'s and dry gas, usually in amounts of less than 10-15% by weight of the charge.

In the reforming operation a relatively small amount of products boiling above the end point of the desired reformed gasoline may be formed. Such higher boiling products can be recycled to hydrogenative cracking as indicated at 14.

The following example illustrates a combined cracking-reforming operation in accordance with the invention.

An East Texas gas oil is charged comprising a crude distillate from which up to 56% of lighter ends and 23% of bottoms were removed, said gas oil having an API gravity of 28.9° and boiling in the range of 539° F. to 928° F. at 95%. This charge is hydrogenatively cracked over a catalyst comprising 2% nickel on calcined silicalumina gel (87.5 SiO₂-12.5 Al₂O₃), under conditions including a pressure of 3500 p. s. i. and a temperature of 825° F., oil being fed at the rate of one volume per hour per volume of catalyst, and 4.7 mols of hydrogen being added to the charge (based on total hydrocarbons). Operating at a recycle ratio of 1.4/1, the following yields were obtained in a 44 hour period:

Yields:

Conversion	100%.
C ₄ -free gasoline	99.1% (vol.).
C ₄	17.8% (vol.).
Dry Gas	8.3% (wt.).
H ₂ Consumption	1600 cu. ft./bbl.

Gasoline inspection:

Octane No.:

CFR-M	62.
CFR-R Clear	64.
CFR-R+3 cc. TEL	84.

The gasoline from the above operation was fractionated to provide a light fraction and heavier naphtha fraction as follows:

(45%) Fraction I (70-230°):

Octane No.:

CFR-M Clear	82
CFR-R+3 cc. TEL	93

(55%) Fraction II (230-375° F.) (containing 31% naphthenes), Octane No.: CFR-M Clear 51

Fraction II above was subjected to dehydrogenation over a catalyst comprising 1.2% Pt on precipitated MgO at a temperature of 950° F. and a pressure of 600 p. s. i., operating at a space velocity of 2 volumes of oil per hour per volume of catalyst, with the addition of 3 mols of hydrogen per mol of charge. The yields obtained are given below:

Yields:

C ₄ -free gasoline, vol. per cent	89.
CFR-M Clear	67.8.
CFR-R Clear	78.5.
CFR-R (+3 cc. TEL)	94.
C ₄ , vol. per cent	6.7.
Dry gas, wt. per cent	3.0.
H ₂ , produced	1100 cu. ft./bbl.
	naphtha.

The reformed fraction II is recombined with the light gasoline fraction I from above and the hydrogen is recycled, enough of the C₄'s produced being added to bring the gasoline to 10 pound RVP.

The overall balance for the combined operation is as follows:

Gasoline (C ₅ +), vol. per cent	94.5
CFR-R (+3 cc. TEL)	93.5
C ₄ , vol. per cent	21.5
Dry gas, wt. per cent	9.3

The addition of 5-8% of the C₄ fraction to the above gasoline to bring the same to 10 pounds RVP, will raise the octane numbers of the stabilized gasoline at least about a point.

Obviously many modifications and variations of the invention as hereinbefore set forth may be made without departing from the spirit and scope thereof, and therefore only such limitations should be imposed as are indicated in the appended claims.

We claim as our invention:

1. The method of producing high yields of gasoline of good octane quality which comprises removing from petroleum at least those materials boiling in the range of gasoline to provide an initial hydrocarbon charge, hydrogenatively cracking said initial hydrocarbon charge

- at a pressure in excess of about 750 pounds per square inch and in the presence of a catalyst composed of a minor quantity of a component having selective hydrogenating activity intimately associated with a component having cracking activity, removing a hydrogen-rich gas stream from the effluent, separating the remainder of the effluent into fractions comprising at least: a C-4 fraction, a light gasoline fraction of comparatively high octane value composed of hydrocarbons boiling above the C₄ fraction and below 240° F., a cracked naphtha fraction including naphthenic hydrocarbons boiling in the upper portion of the gasoline range, and a residual gas oil fraction boiling in a range above said last named naphtha fraction; continuously and exhaustively recycling said residual gas oil fraction to said hydrogenative cracking, reforming only said cracked naphtha fraction substantially free from lower boiling hydrocarbons under dehydrogenating conditions and in the presence of a dehydrogenating catalyst, said conditions and catalyst being selected to disfavor substantial coking and cracking of said naphtha fraction including pressure above 300 pounds per square inch, recovering from products of dehydrogenation a hydrogen-rich gas and a reformed gasoline fraction of desired end point, returning at least a portion of said hydrogen-rich gas from dehydrogenation to said hydrogenative cracking step, blending said reformed gasoline fraction with said light gasoline fraction derived from hydrogenative cracking and adding to the blend a sufficient portion of said C-4 fraction to produce gasoline of desired vapor pressure, and recycling to hydrogenative cracking any hydrocarbons boiling above the desired end point of the reformed gasoline, whereby all of the hydrocarbons in said initial charge are converted to products boiling no higher than said desired gasoline end point.
2. The method according to claim 1 wherein said hydrogenative cracking of the initial charge is carried out at temperatures in the range of about 800-1000° F. and at pressures of at least 1500 pounds per square inch.
3. The method according to claim 2 wherein the catalyst employed in the hydrogenative cracking step consists of a silicious cracking component containing nickel as hydrogenating component.
4. The method according to claim 1 wherein the reforming of said cracked naphtha fraction is effected at temperatures in the range of 700-1050° F., under pressure of 500 to 1500 pounds per square inch.
5. The method according to claim 1 wherein said effluent from hydrogenative cracking is separated into fractions including a normally gaseous hydrocarbon fraction.
6. The method according to claim 5 wherein said normally gaseous hydrocarbon fraction is converted to products including hydrogen and said hydrogen is recovered for use in said hydrogenative cracking.
7. The method according to claim 1 wherein said light gasoline fraction separated from the effluent from hydrogenative cracking has an end point of about 180-240° F. and said cracked naphtha fraction boils in a range thereabove and up to 350-450° F.
8. The method according to claim 1 wherein operating conditions are maintained during said hydrogenative cracking to effect 20-60% conversion of said initial charge.
9. The method according to claim 8 wherein said operating conditions include temperatures below 900° F., pressure of 1500-3500 pounds per square inch, liquid space velocity of about 0.5 to about 4 volumes of hydrocarbon charge per hour per volume of catalyst, at least 5 mols of hydrogen being added per mol of total hydrocarbons charged.
10. The method according to claim 1 wherein said cracked naphtha fraction is reformed in the presence of a catalyst comprising platinum on an inert carrier having no substantial cracking activity and at a temperature of about 950° F., said cracked naphtha being charged at a liquid space rate above about 1 volume of naphtha per hour per volume of the catalyst.
11. The method of producing high yields of gasoline of good octane quality and high lead susceptibility which comprises feeding a reduced petroleum crude of essentially above gasoline boiling range to a hydrogenative cracking zone containing a catalyst composed of a silicious cracking component of high cracking activity intimately associated with up to about 5% of a component selectively promoting hydrogenation reactions, said crack-

ing zone being maintained at a temperature in the range of about 800-900° F., under a pressure of 1500-3500 pounds per square inch, at least three mols of hydrogen being charged to said cracking zone per mol of total hydrocarbons including recycle, and said total hydrocarbons being fed to said cracking zone at a liquid space rate of 0.5 to 4 volumes of oil per hour per volume of catalyst; recovering from the vapor effluent from said cracking zone a gas rich in hydrogen and a bottoms fraction having an initial boiling point of 350-450° F., continuously and exhaustively recycling said bottoms fraction and a portion of said hydrogen-rich gas to said hydrogenative cracking zone, further separating from the vapor effluent a fraction consisting essentially of normally gaseous hydrocarbons and a C₄ fraction, separating the remaining hydrocarbons in said effluent into at least two fractions including a comparatively high octane light gasoline fraction having an end point in the range of 180-240° F. and a poor octane cracked naphtha fraction boiling in a range thereabove and comprising naphthenic hydrocarbons, subjecting only said cracked naphtha fraction to a reforming operation, involving selectively dehydrogenating naphthenes in said cracked naphtha fraction in a reforming zone containing a dehydrogenation catalyst having no significant cracking activity, said zone being maintained at a temperature in the range of 700-950° F. and under a pressure of 500-1500 pounds per square inch, at least 3 mols of hydrogen per mol of naphtha being charged to said reforming zone

and said naphtha being charged to said zone at the rate of at least 1 liquid volume per hour per volume of catalyst, whereby no significant coke deposits in said reforming zone, separating a hydrogen-rich gas from products formed in said reforming zone and returning said gas to said cracking zone, and blending reformed gasoline from said reforming zone with the light gasoline fraction from said cracking zone and sufficient C-4 hydrocarbons therefrom to adjust the thus upgraded gasoline to desired vapor pressure.
